UNITED STATES PATENT OFFICE.

OTTO FOX, OF LAKWOOD, OHIO, ASSIGNOR TO THE BRYANT HEATER MANUFACTURING COMPANY, OF CLEVELAND, OHIO, A CORPORATION OF OHIO.

WATER HEATER.

Application filed January 23, 1922. Serial No. 531,022.

This invention relates to improvements in water heaters, and in certain respects is an improvement over the construction shown in my prior Patent No. 1,025,389, patented May 5, 1912.

In my prior patent I have shown a water heater, the heater or boiler proper of which is composed of a number of cast sections arranged side by side, and each having upright portions connected by transverse and slightly inclined ducts or tubes. These ducts or tubes of adjacent elements are staggered, and they have lateral and vertical wings, the lateral wings or extensions of each element 10 overlapping the similar wings of adjacent elements.

The heater shown in my prior patent is effective, but by the present invention is improved in certain particulars, resulting in 20 increased efficiency, these improvements residing in the form and arrangement of the lowermost tubes or ducts of the heater.

One of these improvements consists in bringing the lower portions of the lower 25 series of cross tubes of all the parallel heater elements substantially the same distance from the burners.

Another improvement resides in so forming the lower series of cross tubes that they 30 have less tendency to restrict the upward flow of heat than do the tubes above.

The invention may be further briefly summarized as consisting in certain novel details of construction, and combinations and 35 arrangements of parts which will be described in the specification and set forth in the appended claims.

In the accompanying sheets of drawings showing the preferred embodiment of my 40 invention, Fig. 1 is a view looking toward the front of my improved heater, with a portion thereof in section, substantially along the irregular line 1—1 of Fig. 2; Fig. 2 is a side view with the outer wall of the 45 heater removed; Fig. 3 is a side view of one of the heater elements removed; Fig. 4 is a top plan view of the heater with the cover or top removed, and with the two opposite side walls in section; and Fig. 5 is 50 an enlarged sectional view showing the tubes in the lower part of the heater.

My improved heater includes a base 10 which may have any suitable construction, and which carries a plurality of burners 11 55 adapted to be supplied with gas from a pipe.

12. On this base is supported a plurality of water circulating elements 13, in the form of castings arranged side by side. Aside from the shape and arrangement of the lowermost cross tubes of these castings, 60 the details of the latter are immaterial, though in a general way they are similar to the water circulating elements of my prior patent, but in this instance each is formed of one casting instead of two castings, as 65 shown in my patent.

Each casting or water circulating element 13 has along the sides, upright conduit portions 13^a, 13^b, and these conduit portions are connected together by cross tubes 14, 70 forming water ducts, these tubes, as in my prior patent, being slightly inclined from the horizontal. These cross tubes of adjacent elements are staggered, as clearly shown 75 in Fig. 1, and they have wings or extensions which project vertically and laterally, and the lateral extensions of the tubes of each element overlap the similar extensions of the tubes of the adjacent element or elements. 80

The lower rear portions of the elements have boss-like extensions 15, these extensions engaging one another, and being connected together and constituting in effect an inlet header with which all the elements communicate. Likewise, the upper front portions of the castings have similar boss-like extensions 16 which engage one another and are connected together, forming in effect an outlet header or water outlet, these 85 portions 16 communicating with the upper front part of the water circulating elements. The rear upright walls of the heating elements 13 abut for their full length, forming 90 a closed rear wall, but preferably the front upright portions of the elements are slightly spaced apart for cleaning purposes, but the spaces between them are closed by upright closure members 17, held in place by clamps 18^a. Additionally the sides of the 95 boiler are closed by side walls 18 with flanges 18^b which project inwardly between the lateral wings or extensions of the cross tubes of the two outer elements 13. Additionally the heater is provided with a suitable top or 100 cover 19.

In my prior patent the shape of the lowermost cross tubes are identical with the shape of the cross tubes above them, and in view of the fact that the cross tubes are 110

staggered, the lowermost tubes of alternate water circulating elements are a considerable distance above the burners so that the bottom tubes of part of the elements are 5 considerably less effective for heating purposes than the bottom tubes of the other elements which are closer to the burners.

The one important improvement which I have made consists in bringing the bottom 10 portions of the bottom tubes of all the elements to the same, or substantially the same level. In the drawings, the bottom tubes of certain of the elements (two in this instance) are designated 14^a, and the bottom 15 tubes of the other alternate elements (three in this instance) are designated 14^b. In accordance with my invention, the lower portion of tubes 14^a are brought to, or substantially to the same level as the lower portions 20 of the tubes 14^b. This is accomplished by extending the bottom wings of the tubes 14^a considerably lower than in the tubes above them. Also the tubes 14^a are lowered somewhat from the tubes immediately above 25 them, whereas the tubes 14^b are elevated slightly or brought somewhat closer to the tubes immediately above them as regards the spacing between the remainder of the tubes of each element.

30 Furthermore, when the tubes are all alike, as shown in my prior patent, I find that the upward flow of the heat is considerably obstructed by the lateral wings of the lowermost tubes causing a too intense heating action at this point, and I find that the efficiency of the heater is considerably improved by so forming the lowermost tubes of the several elements 13 that they will have a less heat obstructing effect than the 35 tubes above, and it will be observed that the lowermost tubes of the different elements 13 are narrower than the remaining tubes, that is to say, the lateral extensions are shorter. Likewise the bottom extensions merge more 40 gradually into the lateral extensions, thus avoiding abrupt changes in shape or curvature, and providing a less baffling effect than is produced by the tubes above the lowermost. On the other hand, the heat can pass 45 upward quite freely between the lowermost tubes.

50 Thus while tortuous passageways are provided for the heat from the bottom to the top of the heating elements, nevertheless, 55 there is little restriction or baffling at the bottom, as is desired, whereas there is a considerable baffling by the overlapping wings of the tubes above the lowermost tubes, as is desired.

60 By these changes in the shape and relative arrangement of the lowermost tubes, the efficiency of the heater as a whole is improved.

I do not desire to be confined to the exact 65 details shown, but aim in my claims to cover

all modifications which do not involve a departure from the spirit and scope of my invention as defined in the appended claims.

Having described my invention, I claim:

1. A water heater comprising a series of 70 water circulating elements arranged side by side and each comprising upright water conveying portions and transverse ducts extending between the same, burners arranged beneath the elements, the ducts of adjacent elements being staggered, and the bottom portions of the lowermost ducts of said elements being at substantially the same level.

2. In a water heater, a plurality of water 80 circulating elements arranged side by side and each comprising upright portions and transverse ducts connecting the same, all for the circulation of water, the ducts of adjacent elements being staggered, the bottom portions of the lowermost ducts of the different 85 elements being more nearly in the same level than the bottom portions of the ducts above the lowermost.

3. In a water heater, a plurality of water 90 circulating elements arranged side by side and each comprising upright portions and transverse ducts connecting the same, all for the circulation of water, the ducts being arranged in superposed series, with the ducts 95 of each series staggered, and the ducts having lateral extensions, the lateral width of the ducts of the lowermost of the superposed series being less than the lateral width of the ducts above the lowermost series.

4. In a water heater, a series of water 100 heating elements arranged side by side and each composed of upright portions and transverse ducts, the ducts being provided with staggered lateral extensions forming tortuous passageways for the heat, the passageways 105 being the lowermost ducts being less tortuous than between the ducts above the lowermost.

5. In a water heater, a plurality of water 110 circulating elements arranged side by side, burners beneath the same, each element being composed of upright portions and transverse tubes, all of the tubes being provided with lateral extensions, the extensions of the tubes of one element projecting into the space between extensions of tubes of adjacent elements, whereby tortuous passageways are 115 formed between adjacent tubes for baffling the heat in its upward travel between the tubes, the passageway between the lowermost tubes of adjacent elements being less tortuous than between the tubes above the lowermost.

6. In a water heater, a plurality of adjacent water circulating elements, burners arranged beneath the same, each element being composed of upright portions and connecting tubes, the tubes of adjacent elements having lateral extensions, the extensions of the tubes of one element projecting into the space between extensions of tubes of adjacent elements thereby forming tortuous passage- 120 125 130 135

ways for the heat, the opposed sides of the lowermost tubes of adjacent elements having more of a vertical disposition than the tubes above the lowermost whereby said lowermost tubes have less baffling effect than the tubes above the lowermost.

7. In a water heater, a plurality of heating elements, each provided with upright portions and with transverse connecting tubes, the tubes of adjacent elements having lateral extensions, the extensions of the tubes of one of the elements projecting into the

spaces between extensions of tubes of adjacent elements, thereby forming tortuous passageways for the heat, the juncture of the bottom and laterally extending portions of the lowermost tubes of said elements being less abrupt than in the tubes above them whereby the baffling effect of the lowermost tubes is less than that of the tubes above the lowermost.

In testimony whereof, I hereunto affix my signature.

OTTO FOX.
